ELECTRIC FENCE CHARGING APPARATUS

William F. Fagen, Chicago, Ill., assignor to
Stewart-Warner Corporation, Chicago, Ill., a
corporation of Virginia

Application November 15, 1943, Serial No. 510,307

25 Claims. (Cl. 256—10)

1

The present invention relates to electric fences, and more particularly to automatically operable fence energizers or chargers.

An object of the present invention is to provide a new and improved fence charging apparatus producing but a single energy impulse of short duration when the fence is contacted by an animal. An advantage of the device of the present invention is that it enables the animal to clear itself from the fence without being subjected to continued inhumane application of electric shocks irrespective of whether or not the animal is entangled with the fence.

Another object of the present invention is to provide a new and improved fence charging apparatus of the character aforesaid, wherein the fence charging apparatus is controlled to provide an impulse of energy in response to a change in an electric current, preferably a change in current flow through the fence occasioned by contact between the fence and the body of an animal.

A further object of the present invention is to provide an electric fence charging apparatus wherein a relatively low voltage is normally applied to the fence and wherein a relatively high voltage impulse is passed through the fence in response to contact between the fence and the body of an animal. The use of a low normal or stand-by voltage has a number of advantages. Less difficulties are encountered because of circuit unbalance resulting from dampness, showers, branches brushing against the fence, and the like. Furthermore, the high voltage impulse is not produced as a result of contact between the fence and branches and the like.

A further object of the present invention is to provide a new and improved fence charging apparatus wherein a single energy impulse is produced upon initial contact between the fence and the body of an animal, and wherein a plurality of such impulses occur when the fence is contacted sequentially by a plurality of animals.

Another object of the present invention is to provide a new and improved electric fence charging apparatus including a normally inoperative energy impulse supplying means which is rendered operative and effective to supply an energy impulse to the fence substantially immediately an animal comes into contact with the fence. This is of advantage in conditioning the animals to stay away from the fence.

A further object of the present invention is to provide an electric fence charging apparatus capable of producing a high voltage energy impulse but which does not require any high voltage power source.

2

A further object of the present invention is to provide an electric fence charging apparatus of the electronic type comprising relay means, preferably of the electronic type, and a transformer inductively coupled to the fence, and having also means for producing a current impulse in the primary of the transformer whenever an animal contacts the fence, thereby to provide a high voltage energy impulse of short duration.

A further object of the present invention is to provide an electronic fence charging apparatus wherein the energy impulse is substantially independent of the contact resistance between the animal and the fence.

A more specific object is to provide an apparatus of the character last specified wherein the constant impulse is produced by effecting saturation of one or more of the electron tubes employed, and more particularly by utilizing a first energy impulse to produce a second energy impulse effecting said saturation. The two impulses occur substantially simultaneously so that there is in effect produced but one energy impulse which is transmitted through the fence to the animal.

Another more specific object is to provide an apparatus of the character specified in the second preceding paragraph wherein the energy impulse is made substantially independent of the contact resistance by means not requiring the production of a second energy impulse.

A further object of the present invention is to provide a new and improved electronic fence charger so constructed and arranged that a definite time interval must lapse before a second energy impulse can be produced.

A further object of the present invention is to provide a new and improved electric fence charging apparatus producing but a single energy impulse when an animal contacts the fence, or which may be selectively arranged to produce periodic impulses, and in which, even though connected for the production of periodic impulses, an impulse is produced upon contact between the fence and an animal.

A further object of the present invention is to provide a new and improved electronically controlled fence charging apparatus so constructed and arranged that the electron tubes thereof will not be injuriously affected even though the impulses applied to the fence are of high voltage and this high voltage is utilized to control the operation of the tubes.

Another object of the present invention is to provide a new and improved electric fence charging apparatus wherein the sensitivity of opera-

tion may be adjusted readily in order that the apparatus may be adjusted to operate under varying atmospheric conditions producing different leakage resistances to ground and contact resistances between the fence and the animal coming into contact with it.

A further object of the present invention is to provide a new and improved electric fence charger which will operate more effectively despite variations in leakage resistance to ground. More specifically, it is an object of the present invention to polarize the fence wire positively by the application of a positive potential to the fence, whereby the leakage resistance to ground is considerably increased to render the operation of the apparatus more certain.

A further object of the present invention is to provide a new and improved fence charger of the electronic type in which the requisite shocking impulse is produced by an electron tube which is rendered conductive in response to a control impulse and which passes considerable current to produce the impulse when rendered conductive.

Another object of the present invention is to provide an electric fence charger having lightning protection means.

Another object of the present invention is the provision of new and improved electric fence charging equipment which will not operate in response to stray voltages, such, for instance, as may be derived from high tension lines in proximity to the fence, unless the stray voltages are above an abnormally high value.

Other objects and advantages of the present invention will become apparent from the ensuing description, in the course of which reference is had to the accompanying drawings, in which:

Figs. 1 to 3 are diagrammatic representations of various embodiments of the present invention.

The embodiment illustrated in Fig. 1 includes a fence charging apparatus 10 constructed in accordance with the present invention, the input of which is adapted to be connected through a plug type connector 12 to a suitable source of power, such, for instance, as 110 volts alternating current, and the output of which is adapted to be connected to the bare conductive wire 14 of the fence and to ground through a conductor 16. An on-off switch 18 is utilized to control the supply of power to the apparatus.

The fence wire 14 may be supported upon a number of fence posts 20 (of which only one has been illustrated), placed in the earth in conventional manner. It should be understood that in some installations it is preferable to use two fence wires, one corresponding to the single wire 14 illustrated, and the other to the earth or ground connection. It should be understood also that the term "fence" is not limited to fences for pastures or other enclosures for cows or horses or the like, but is intended to be broad enough to include protective safeguards for houses, rooms and the like to prevent, or tend to prevent, human beings from entering or leaving the premises.

The apparatus of the present invention includes a normally inoperative energy impulse producing means which is controlled in response to contact between the fence wire and an animal to produce an energy impulse through the wire and the animal in contact with the wire. The apparatus includes in the main, a source of power, control and amplifying means, and impulse producing means, these being indicated generally by reference characters 22, 24 and 26, respectively. The apparatus is so constructed and arranged

that a control voltage is produced when an animal contacts the fence. This control voltage is amplified by the amplifier 24 and produces a current impulse in the impulse producing means which in turn generates a voltage. The voltage thus generated is applied to the fence and also re-applied to produce a further control voltage that is amplified and utilized to produce a further voltage impulse which is of substantially constant value and independent of contact resistance between the fence and the animal and which is applied to the fence to produce the requisite "shock" acting to deter animals and the like from leaving the enclosure. The two impulses occur so rapidly, however, that they constitute, in effect, but a single impulse.

The power source 22 is illustrated as being of the electronic type, including a rectifier tube 30 (preferably of the 5Y 3G type) energized by a transformer 32 and supplying a low direct current voltage preferably of about 300 volts across resistor 34 (of a value of about 50,000 ohms). The transformer 32 includes a primary winding 36 and three secondary windings 38, 40 and 42. Winding 38 has its terminals connected to the anodes of the tube and its center point to conductor 44 leading to the negative terminal of resistor 34. Secondary winding 40 is connected to the filament of tube 30 and the latter is connected through a choke coil 46 to conductor 48 connected to the positive terminal of resistor 34. The terminals of the choke coil 46 are connected to conductor 44 by the usual filter condensers 49. Secondary winding 42 is utilized to supply current to the cathode heaters of the remaining electron tubes of the system, to which reference will be had shortly. It should be understood that while an electronic power supply has been illustrated, a battery could also be used to supply the requisite voltage across resistor 34.

The energy impulse supplying means includes a condenser 50 and relay means in the form of an electron tube 52 (preferably of the 6L 6G type) having in its output circuit the primary winding 54 of a transformer 56, the secondary winding 58 of which is connected to the junction of conductors 48 and 16 and to the fence wire 14 through a blocking condenser 60 (of a value of about .25 mf.). The condenser 50 is connected across the major portion 34A of resistor 34 so that it is normally charged to a voltage slightly less than that appearing across the resistor.

The tube 52 is normally biased to cut-off by rendering its control grid 62 more negative than its cathode 64. The negative bias is obtained by connecting the grid to the negative terminal of resistor 34 and the cathode to a more positive portion of that resistor. A portion 34B of the resistor is thus effectively in series with the cathode of the tube. The grid is connected to the negative terminal through a conductor 66, a resistor 68 (having a value of about 100,000 ohms), and a conductor 70. The cathode is connected to the resistor 34 through a conductor 72 having an adjustable connection relative to resistor 34. The tube 52 includes, in addition, a screen grid 74 connected to the plate in conventional manner.

The conductivity of tube 52 is controlled in response to a control voltage resulting from contact between the fence and an animal to produce a current impulse through transformer winding 54 and an energy impulse through the fence wire and the body of the animal contacting the wire. The control voltage is obtained by placing a re-

sistor in the low voltage circuit and utilizing the change in voltage drop thereacross when an animal contacts the fence. In the instant case the low voltage normally applied to the fence is the voltage of slightly less than 300 volts appearing across conductors 48 and 72, the former of which is connected to ground and the latter of which is connected to the fence wire through a resistor 74 (having a value of about 100,000 ohms) and conductor 76. The resistor 74 is utilized, not only in the production of the control voltage but it also serves to limit the leakage current normally flowing from the fence to ground. Inasmuch as the resistor 74 is connected in circuit with the fence wire and ground, it may be seen that whenever the fence is contacted by a terminal there is an increase in current flowing through the resistor 74 and a resulting increased voltage drop which makes the voltage of the fence end of resistor 74 more positive.

A selected portion of the control voltage is applied to relay means comprising the amplifier 24 through a condenser 78 (having a value of about .01 mf.) and a selected portion of resistor 80 (having a value of about 250,000 ohms) which serves as a "volume control." One terminal of resistor 80 is connected to the condenser 78 and the other to conductor 72. A portion of the voltage drop across resistor 80 is applied to the amplifier through an adjustable contact 82 providing a sensitivity control, a selector switch 84, provided for a purpose to be set forth in greater detail hereinafter, and a resistor 86 (having a value of about 50,000 ohms). The resistor 86 is provided to act as a safeguard in the event resistor 80 is cut out entirely.

The condenser 78 has a value such that slow changes in current flow through resistor 74, and therefore slow changes in voltage drop thereacross, will not be applied to the amplifier to produce an energy impulse. This construction thus prevents the apparatus from producing an energy impulse in response to slow or slight variations in resistance between the fence wire and ground, as might be caused by dampness and showers and by branches contacting the fence. Furthermore, the normal biasing of the tube 52 to cutoff, as heretofore mentioned, precludes the possibility of the tube being rendered conductive when an animal disengages itself from the fence and produces a control impulse of opposite polarity to that produced upon contact. This is an advantage in that a shocking impulse is applied to the fence circuit only when an animal engages the fence.

The amplifier 24 may take various forms, and the one illustrated is of the two-stage resistance coupled type. A single duplicate section high gain tube 90 (preferably of the 6SC7 type) is used. The first section includes a cathode 92, a control grid 94 and a plate 96. The second section includes a cathode 98, a grid 100 and a plate 102. The two cathodes are connected together and to conductor 72 through a self-biasing resistor 104 (having a value of about 2,000 ohms) which is bypassed by a condenser 106 (having a value of about 10 mf.). Plates 96 and 102 are connected to the positive supply line 48 through resistors 108 and 110, respectively.

The control voltage obtained from across resistor 74 is applied to the grid 94 of the first tube section through a circuit including the previously referred to condenser 78 and resistors 80 and 86. The control voltage is amplified by the first section and supplied to the grid 100 of the second

section through a coupling condenser 112 (having a value of about .01 mf. or somewhat larger) and a coupling resistor 114 (having a value of about 250,000 ohms). The amplified control voltage is applied to the grid 62 of tube 52 to render the latter tube conductive for a brief interval. The grid 62 is connected to the output of the second section of tube 90 through a coupling condenser 116 (having a value of about .01 mf. or somewhat larger) and the previously referred to resistor 68 which also constitutes a coupling resistor.

When an animal contacts the fence, there is thus produced a control impulse which is amplified and applied to the grid of tube 52 to render the latter conductive so that the condenser 50 discharges through it. The discharge current flows through the primary 54 of transformer 56, thereby inductively to apply an energy impulse to the fence wire. In accordance with another feature of the present invention, the first impulse is re-applied to the amplifier and tube 52 to render the actual energy impulse supplied through the fence and animal substantially independent of contact resistance between the animal and the wire. It may be noted that when the first voltage impulse is applied to fence wire 14, the voltage of that wire is changed and the secondary winding 58 is so connected to the ground and fence that the voltage impulse produces a flow of current through resistor 74 in a direction to render the fence end of the resistor more positive; i. e., the current flow is the same as when the animal first contacted the fence. The conductivity of tube 52 is thereby quickly increased to some value determined by which of the circuit elements saturates first. In properly designed apparatus the various circuits may be so arranged that they all saturate at more or less the same time, although in an apparatus of the character described herein it is probably the first triode section of tube 90 that saturates first.

The two impulses occur so rapidly that they are in effect a single impulse. This impulse may produce a peak voltage across secondary winding 58 (when this winding is open circuited) of several thousand volts, perhaps as much as 7,000 volts. In order to prevent this high voltage from being applied to the grid 94 of tube 90, a cold cathode gas discharge tube 120 is connected across the grid and conductor 72. This tube is normally nonconductive, but when the voltage reaches some predetermined high value, say, of about 90 volts in the instant embodiment, the tube becomes conductive and thus limits the voltage.

The current impulse flowing through the tube 52 and transformer winding 54 is supplied by the condenser 50 and by the main power supply 22. In the illustrated embodiment where the resistor 34 has a value of about 50,000 ohms, the condenser and resistor both supply power for producing the energy impulse, but if the value of resistor 34 is increased to about 1 megohm, then the condenser supplies most of the power. In both cases the condenser supplies the power for producing the initial high energy or peaked portion of the impulse. After the initial impulse the current decreases rapidly to a safe minimum value because of a reduction in the control voltage applied to the amplifier and because the grid 94 of the first section of the amplifier is made less positive with respect to the cathode. This results because of two factors, one being a decrease in the voltage of the impulse and the second being the result of the flow of discharge current through the portion 34B of resistor 34 which is in series with the cathode 64 of the tube 52. The flow of current through the

resistor portion 34B makes the cathodes of the tube 90 more positive relative to the grids, thereby reducing in effect the positive potential of the grids relative to the cathodes.

The apparatus of the present invention may also be arranged to apply periodic impulses to the fence wire upon operation of the selector switch 84 to its uppermost position wherein the resistor 86 is connected to the junction of condenser 78 and resistor 80 through conductor 122. This in effect amounts to adjusting the volume control to increase the volume. The gain of the amplifier is then increased to so high a value that slight changes cause pulses to be produced in much the same manner as "motorboating" is produced in amplifiers. Periodic impulses can also be produced by decreasing the negative grid bias on tube 52 whereby that tube can be rendered conductive by the application of smaller control voltages thereto.

When the apparatus is conditioned for the production of periodic impulses it will also produce a further impulse upon contact, in the manner described above, i. e., by the production of a control voltage appearing across resistor 78.

The periodicity of the impulses may be adjusted by varying the value of resistance included in resistor portion 34B, which varies the grid bias of tube 52 and also by varying the size of condenser 50. The larger the condenser the greater is the time required to charge it to a value such that the voltage applied to the plates of the various tubes is high enough to enable them to be rendered conductive in response to the control voltage.

In the following description of the operation, it will be assumed that the selector switch 84 is in its indicated position and the power switch 18 is closed to condition the apparatus for operation. Under normal conditions a relatively low direct current voltage is applied to the fence by the power supply 22, the positive terminal of which is connected to ground and the negative terminal of which is connected to the fence wire 14 through conductor 16 and the control resistor 14.

When an animal contacts the fence the current flow through resistor 14 is increased, thereby to provide a control voltage which is amplified to render the tube 52 conductive and to produce an energy impulse which is reapplied to the amplifier to saturate the system and quickly render tube 52 conductive enough so that the condenser 50 may discharge therethrough and through the primary winding of transformer 56. The flow of current through the primary winding of the transformer inductively produces a brief flow of high voltage current through the animal in contact with the fence, thereby to produce the requisite electric shock to deter the animal from going through the fence. This impulse is of short duration and quickly decreases to a safe value, at which it remains as long as the animal is in contact with the fence. If the animal leaves the fence, then after a time interval determined primarily by the size of condenser 50, the apparatus is ready to produce another impulse. No shocking impulse, however, is applied to the fence circuit when an animal leaves or disengages itself from the fence because of the heretofore referred to biasing of tube 52 to cutoff.

The apparatus will also produce a further impulse if a second animal comes into contact with the fence after the first has been in contact with the fence for a time interval long enough to enable the condenser 50 to be recharged. When

the second animal contacts the fence the flow of current through resistor 54 is again increased to render the amplifier effective to make the tube 52 more conductive in the manner heretofore described. The occurrence of the shocking impulse substantially immediately upon contact is of advantage in conditioning the animals to remain away from the fence.

If it is desired to apply periodic impulses to the fence, the selector switch 84 is moved upwardly to complete a circuit to conductor 122. This periodic application of impulses to the fence may be advantageously used in training the animals.

The sensitivity of operation of the apparatus may be adjusted by movement of the adjustable contact 82. This is an advantage in that the apparatus may be readily adjusted to provide the requisite shocking impulse under various atmospheric conditions under which the leakage resistance to ground and the contact resistance between the animal and ground may vary between relatively wide limits. It is preferred that the sensitivity adjustment be such that the shocking impulse will be produced with a contact and leakage resistances of 50,000 ohms or upon a contact and leakage resistances of 25,000 ohms.

The discharge tube 120 not only serves to limit the voltage applied to the amplifier tube to a safe value, but it also serves as an indicator of the operation of the apparatus. Each time an impulse is applied to the fence the tube is rendered conductive to indicate the application of the impulse. The tube also provides lightning protection as it breaks down and prevents the application of high voltages to the amplifier, etc.

The embodiment of the invention illustrated in Fig. 2 is in many respects similar to that of the first embodiment. However, there are some differences. In the first place, the control voltage is so connected to the fence that the fence wire 14 is maintained at a positive potential, and in the second place the impulse producing circuit is substantially independent of the control circuit. The maintenance of the fence wire at a positive potential results in a marked decrease in the leakage current because the leakage resistance to ground is considerably greater when the wire is made positive than when the wire is made negative. It appears that there is present a definite polarity effect making the leakage resistance considerably higher when the wire is positive. It appears further that this polarity effect results from the contact of the wire with vegetation and that the leakage resistance increases after the connection of the voltage to the wire, and that this increase is present, however, only when the wire is made positive with respect to ground. Thus by polarizing the fence wire positively by the control voltage, it is possible to secure effective operation of the apparatus when other controllers may be inoperative because of low leakage resistance to ground.

Referring now to Fig. 2, it may be noted that the fence charging apparatus is supplied with power by a full wave rectifier indicated generally by the reference character 132 and including a tube 134 (which may be of the 6X5GT type). The rectified direct current output appears across the conductors 136 and 138, the latter of which is the negative line and is connected to ground.

The positive control voltage is applied to the fence wire through a filter resistor 140 (which may have a value of 25,000 ohms), a conductor 142, and a control resistor 144 (which may have a value of 100,000 ohms) corresponding to the con-

trol resistor 74 of the previously described embodiment. A filter condenser 148 is connected across conductors 142 and 138. As heretofore indicated, the maintenance of the fence wire at a positive voltage increases the leakage resistance from the wire to ground and thus also decreases the leakage current.

The apparatus also include relay means in the form of a control and amplifying means indicated generally by the reference character 148. This means includes a tube 150 similar to the tube 90. The cathodes 152 and 154 of the two sections of the tube are connected to conductor 138 through resistor 158 (which may have a value of about 600 ohms) shunted by a condenser 158 (having a value of about 10 microfarads). The plates 160 and 162 are connected to conductor 142 through resistors 164 and 166, respectively (each having a value of about 100,000 ohms). The grid 168 of the second tube is connected to plate 160 through a coupling condenser 170 (having a value of about .02 microfarad), and it is also connected to conductor 138 through resistor 172 (having a value of about 100,000 ohms).

A selected portion of the control voltage appearing across resistor 144 when an animal contacts the fence is applied to the grid 174 of the first section of tube 150. The grid is adjustably connected by a conductor 176 to a resistor 178 to provide a sensitivity control (the resistor has a value of about 250,000 ohms). One terminal of the resistor 178 is connected to conductor 138 by the conductor 180, and the other terminal is connected to the fence wire through a resistor 182 (having a value of about 100,000 ohms), a condenser 184 (having a value of about .01 microfarad), and conductor 186. The condenser serves to prevent operation of the amplifier to produce energy impulses unless the change in current flow through the resistor is quite rapid, thereby to prevent the production of an energy impulse in response to slow variations in resistance between the fence and ground as might be caused by dampness, showers, and the like.

In order to prevent injury to the apparatus as by the application of excessive voltages to the grid 174 of tube 150, the resistor 178 is shunted by a protecting neon lamp 188 which, like the lamp 120 of the proceeding embodiment, breaks down at a voltage of about 90 volts. This tube 50 also provides lightning protection.

The impulse producing means of the present embodiment includes a condenser 190 (having a value of about 2 microfarads), a gas tube 192 (which may be of the 631P1 type), and the primary winding 194 of a transformer 196. The arrangement is such that when the tube 192 is rendered conductive the condenser 190 discharges through the tube and through the primary winding 194 of the transformer. The plate 198 of the gas tube is connected to one terminal of primary winding 194, the other terminal of which is connected to condenser 190 through conductor 200. The other terminal of condenser 190 is connected to conductor 138. The condenser is also shunted by a resistor 202 (about 470,000 ohms), utilized in the instant embodiment to decrease somewhat the voltage across the condenser and to render the operation more stable. The condenser also acts as a filter condenser for the plate voltage supply. The separate plate voltage supply for the tube 192 and the connection of the condenser 190 in this supply improves the operation of the apparatus because the impulse producing means is more independent of the am-

plifier and there is less tendency to oscillate. The impulse producing tube 192 and condenser 190 are both connected to the power supply through a conductor 204 and a filter resistor 206 (having a value of about 25,000 ohms) connected to the conductor 138.

The tube 192 is rendered conductive in response to the control voltage produced when an animal contacts the fence. The control voltage is amplified by the tube 150 and the amplified voltage is utilized to render the tube conductive by producing a voltage difference between grids 208 and 209 of tube 192. The grid 208 is coupled to the second section of tube 150 by the coupling condenser 210 (having a value of about .02 microfarad) and the coupling resistor 212 (having a value of about 400,000 ohms) and grid 209 is connected to the cathode 214. The cathode 214 of tube 192 is connected to conductor 138 by conductor 216. The voltage difference between grids 208 and 209 is obtained by making grid 208 more negative when the animal contacts the fence, the more negative voltage resulting from the particular polarization, location of resistor 144 and the nature of the amplifying means used. This voltage difference may be of the order of 60 volts where, as here, a plate voltage of about 300 volts is used. If desired, the tube could be rendered conductive by making the grid 208 more positive.

The shocking impulse is applied to the fence wire by the secondary winding 218 of transformer 196 which is connected directly across conductors 14 and 138 through a blocking condenser 220.

Indication of operation of the apparatus to produce an impulse is provided by a lamp 222 similar to lamp 188 connected across conductors 14 and 138 by a resistor 224.

In order readily to test the operation of the apparatus there is provided a manually operated pushbutton switch 226 adapted to close a circuit across conductors 14 and 138 through a resistor 228, thereby to simulate conditions obtaining when an animal comes into contact with the fence. If the apparatus is operating properly an impulse is produced and the lamp 222 glows to indicate the application of the shocking impulse to the fence.

To place the apparatus into operation, it is necessary only to insert the plug connector 12 to a suitable source of alternating current and to close the power switch 18. The transformer 132 is thus energized to render the rectifier tube operative and likewise to activate the tube 150. The rectifier charges the condenser 190 in a short time interval determined by the values of resistors 206 and 202. A positive control potential is also applied to the fence wire 14 to obtain the advantageous increased leakage resistance and decreased leakage current heretofore referred to.

When an animal comes into contact with the fence the flow of current through the control resistor 144 increases, with the result that the grid 174 of tube 150 is rendered more negative. This control impulse is amplified and utilized to render the grid 208 of tube 192 more negative, with the result that the tube becomes conductive as a result of the voltage difference across grids 208 and 209. The condenser 190 thereupon discharges through the tube and through the primary winding 194. The current flowing through the winding induces a voltage in the secondary winding 218 which in turn provides the shocking impulse applied to the animal through the fence wire 14 and the ground connection 138.

In the instant embodiment the arrangement

is such that the circuit "saturates" immediately, i. e., there is no reapplication of the impulse voltage to the amplifier. This advantageous result is obtained by utilizing the gas tube 192 which becomes fully conductive immediately.

The apparatus produces but a single impulse upon contact, and successive impulses cannot be produced in any event except at time intervals predetermined by the values of resistors 202 and 206.

Each time the apparatus operates the indicator lamp 222 is lighted to provide an indication of the operation. This indicator lamp also lights up when the switch 226 is closed, provided, of course, that the apparatus is functioning properly.

The sensitivity of the apparatus may be readily varied by adjustment of the contact 176 to apply more or less of the voltage across resistor 178 to the grid 174 of tube 150.

The embodiment of the invention illustrated in Fig. 3 is quite similar to that of Fig. 2. It differs primarily in that a single lamp 240 is utilized as a combined indicator and protective lamp. The positions of resistor 182 and condenser 184 have also been transposed, and the lamp 240 is connected in parallel with the series connected condenser 184 and resistor 178. The lamp becomes conductive when an impulse is produced to indicate operation and it becomes conductive also in the event lightning strikes the fence to protect the equipment. Other differences reside in the change in values of resistors 140 and 182, these having values of about .5 megohm and .7 megohm, respectively. In addition, resistor 202 of Fig. 2, which was in parallel with condenser 190, has been eliminated, the voltage across the condenser in this case being proper for the particular tube and plate voltage supply.

The operation of the embodiment of Fig. 3 is like that of Fig. 2, so that further description thereof at this point is not deemed necessary.

In many cases the fence wires are located in proximity to high tension power lines and are likely to pick up stray voltages and it is another feature of the present invention to provide an apparatus that will not be operated by stray voltages of a magnitude normally encountered in practice. Preferably the apparatus is constructed so that it will not operate even though the 60-cycle pickup is on the order of 10 volts.

Ordinarily, the high tension wires transmit 60-cycle alternating current. In order to prevent the apparatus from being operated by stray 60-cycle voltages, the amplifiers, in those embodiments in which amplifiers are used, are constructed and arranged to attenuate power frequencies and amplify best frequencies in the order of the pulse rate, which may be in the order of those produced by contact with the wire, which may be predominantly in the order of about 4,000 cycles per second (the pulse duration being of the order of 200 microseconds). Thus in the embodiment of Figures 1, 2 and 3, the amplifiers are supplied through condensers and utilize coupling condensers attenuating 60-cycle current, i. e., the condensers are made smaller so as to pass the desired high frequencies and attenuate the lower frequencies. In the embodiment of Figure 1, condensers 78, 112 and 116 and their associated resistors are designed to provide this attenuation; and in the embodiments of Figures 2 and 3, the condensers 184, 170 and 210 are designed for the same purpose.

From the foregoing detailed description of the

present invention it may be noted that the principles thereof may take various forms. It is contemplated that the invention is not to be limited to the precise constructions disclosed but is to include within its scope all such modifications and variations coming within the scope of the appended claims.

Having described my invention, what I claim as new and desire to obtain by Letters Patent of the United States is:

1. Apparatus for energizing a fence comprising a conductive wire adapted to be placed in circuit with the body of an animal contacting the wire, including in combination, means including normally inoperative energy impulse supplying means adapted to be coupled to the fence wire and adapted when rendered operative to supply an energy impulse to the fence wire, voltage supplying means adapted to be coupled to the fence wire for applying a control voltage to the wire, means adapted to be coupled to the fence wire for producing a change in current flow when an animal contacts the wire, and change responsive relay means coupled to said last mentioned means and controlled in response to a change in current flow occurring above a predetermined rate upon contact between the wire and the body of an animal and controlling said impulse supplying means for rendering the latter operative.

2. Apparatus for energizing a fence comprising a conductive wire adapted to be placed in circuit with the body of an animal contacting the wire, including in combination, normally inoperative energy impulse supplying means including a condenser and a transformer having a primary winding adapted inductively to be coupled to the fence wire and through which the condenser is adapted to be discharged, voltage supplying means adapted to be coupled to the fence wire for applying a control voltage to the fence wire, and means including an electron tube in circuit with the primary winding and condenser, means adapted to be coupled to the fence wire for producing a control voltage in response to a change in current flow in the fence circuit and means including a capacitor of predetermined capacity coupling the tube to said last mentioned means for rendering the tube conductive in response to a change in current flow occurring above a predetermined rate upon contact between the wire and the body of an animal for discharging said condenser through said primary winding and tube.

3. Apparatus for energizing a fence comprising a conductive wire adapted to be placed in circuit with the body of an animal contacting the wire, including in combination, means including normally inoperative energy impulse supplying means adapted to be coupled to the fence wire and relay means controlling said supply means for supplying an energy impulse to the fence wire, means including voltage supplying means adapted to be coupled to the fence wire for applying a control voltage to the fence wire to produce a change in current flow upon contact between the animal and wire, means operable in response to said change in current flow for producing a control voltage and means including amplifier means adapted to be coupled to the fence wire and amplifying the effect of the change coupled to said control voltage producing means and to said relay means for rendering the latter operable to supply an energy impulse upon the occurrence of said control voltage.

4. Apparatus for energizing a fence comprising a conductive wire adapted to be placed in circuit

with the body of an animal contacting the wire, including in combination, means including normally inoperative energy impulse supplying means coupled to the fence wire adapted when rendered operative to supply an energy impulse to the fence wire, voltage supplying means coupled to the fence wire for applying a control voltage to the fence wire, means coupled to the fence wire for producing a control impulse when an animal contacts the fence, means coupled to said last mentioned means for amplifying said impulse, and means coupled to said amplifying means controlled by said amplified impulse and controlling said impulse supplying means to supply an energy impulse to said fence wire which is reamplified and utilized to supply an energy impulse to the fence wire which is independent of the contact resistance between the wire and animal.

5. Apparatus for energizing a fence comprising a conductive wire adapted to be placed in circuit with the body of an animal contacting the wire, including in combination, normally inoperative energy impulse supplying means adapted to be coupled to the fence wire including an electron tube and a condenser dischargeable through the tube adapted when rendered operative to supply an energy impulse to the wire, voltage supplying means adapted to be coupled to the wire for applying a control voltage to the fence wire, change responsive means adapted to be coupled to the fence wire for producing a control impulse when an animal contacts the fence, means coupled to said last mentioned means for amplifying said impulse, and means coupling said amplifying means to said tube for rendering said tube conductive in response to said amplified impulse, thereby to supply an energy impulse to said fence wire which is independent of the contact resistance between the fence wire and animal.

6. Apparatus for energizing a fence comprising a conductive wire adapted to be placed in circuit with the body of an animal contacting the wire, including in combination, means including energy impulse supplying means adapted to be coupled to the fence wire including a condenser and an electron tube adapted when rendered conductive to supply an energy impulse to the fence wire, voltage supplying means adapted to be coupled to the fence wire for applying a control voltage to the fence wire, means also adapted to be coupled to the fence wire for producing a control impulse when an animal contacts the wire, and impulse operated means supplied with said control impulse and controlling the conductivity of said tube to effect the discharge of said condenser.

7. An electric fence charging apparatus including in combination, means coupled to the fence wire including relay means operable to supply an energy impulse to the fence wire, and amplifier means having an input circuit coupled to the fence wire and an output circuit coupled to the relay for operating the relay, the gain of the amplifier being sufficiently high to cause the amplifier to oscillate at a low frequency thereby to effect periodic operation of said relay means and the periodic supply of energy impulses to the fence wire.

8. An electric fence charging apparatus including in combination, means coupled to the fence wire including relay means operable to supply an energy impulse to the fence wire, an amplifier having input and output circuits, means coupling the fence wire to the amplifier input circuit, the amplifier having its output circuit coupled to said relay means and a gain sufficient to set the am-

plifier into oscillation at low frequency, thereby to effect periodic operation of said relay means and the periodic supply of energy impulses to the fence wire, voltage supplying means coupled to the fence wire for applying a control voltage to the wire, and means including means coupling the input circuit of the amplifier to the fence wire operable in response to a change in current flow occurring upon contact between an animal and the fence for supplying a control impulse which is applied to the amplifier to effect operation of said relay to operate said impulse producing means.

9. An electric fence charging apparatus including in combination, means coupled to the fence wire including relay means operable to supply an energy impulse to the fence, an amplifier having input and output circuits, means connecting the fence wire to the amplifier input circuit, said means including a potentiometer resistance coupled to the fence wire and a two position selector switch adapted to apply different portions of the voltage drop across the potentiometer to the amplifier input circuit, voltage supplying means coupled to the fence wire for applying a control voltage to the wire, means coupled to the fence wire and resistance operable in response to a change in current flow occurring upon contact between an animal and the fence wire for supplying a control impulse to the input circuit of said amplifier for operating said relay means, the fence wire, potentiometer resistance, selector switch and amplifier gain being so constructed and arranged that in one position of the switch the relay means is operated to produce energy impulses only in response to said control impulses and in the other position of said switch the amplifier is set into low frequency oscillation and the relay means is operated also to produce periodic energy impulses.

10. Apparatus for energizing a fence comprising a conductive wire adapted to be placed in circuit with the body of an animal contacting the wire, including in combination, means including energy impulse supplying means adapted to be coupled to the fence wire and relay means controlling said supply means for supplying an energy impulse to the fence wire, voltage supplying means adapted to be coupled to the fence wire for applying a control voltage to the fence wire, means adapted to be coupled to the fence wire for producing a control voltage in response to a change in current flow when an animal contacts the wire, amplifier means coupled to said last mentioned means for controlling said relay means controlled in response to said control voltage for rendering said relay means effective to supply an energy impulse, and means for limiting the voltage applied to the amplifier means from said fence wire.

11. Apparatus for energizing a fence comprising a conductive wire adapted to be placed in circuit with the body of an animal contacting the wire, including in combination, means including normally inoperative energy impulse supplying means coupled to the fence wire and relay means controlling said supplying means for applying an energy impulse to the fence wire, voltage supplying means coupled to the fence wire for applying a control voltage to the fence wire, other relay means controlling said first mentioned relay means and coupled to the fence wire and controlled in response to a change in current flow occurring upon contact between the wire and the body of an animal for rendering said first

mentioned relay means effective to supply an energy impulse, and means for varying the sensitivity of said other relay means in response to changes in said current flow.

12. Apparatus for energizing a fence comprising a conductive wire adapted to be placed in circuit with the body of an animal contacting the wire, including in combination, means including normally inoperative energy impulse supplying means coupled to the fence wire and relay means controlling said supplying means for applying an energy impulse to the fence wire, voltage supplying means coupled to the fence wire for applying a control voltage to the fence wire, amplifier means coupling the fence wire to said relay means and controlled in response to a change in current flow occurring upon contact between the wire and the body of an animal for rendering said relay means effective to supply an energy impulse, and means in circuit with the amplifier means for adjusting the input to said amplifier means.

13. Apparatus for energizing a fence comprising a conductive wire adapted to be placed in circuit with the body of an animal contacting the wire, including in combination, energy impulse supplying means adapted to be coupled to the fence wire to supply an energy impulse to the wire, means adapted to be coupled to the fence wire for producing a change in an electrical characteristic occurring at a rate substantially in excess of 60 cycles per second when an animal contacts the wire, and means having a predetermined frequency characteristic coupled to said last mentioned means controlled in response to changes in an electrical characteristic of the fence wire occurring at a rate substantially in excess of 60 cycles per second and controlling said first mentioned means for rendering said first mentioned means effective to supply an energy impulse to said wire.

14. Apparatus for energizing a fence comprising a conductive wire adapted to be placed in circuit with the body of an animal contacting the wire, including in combination, energy impulse supplying means adapted to be coupled to the fence wire and to supply an energy impulse to the fence wire, means associated with the fence wire for producing a control impulse having a duration of the order of 200 microseconds when an animal contacts the wire, and means including an amplifier constructed and arranged to amplify frequencies on the order of that of said control impulse and coupled to said control impulse and energy impulse supplying means for rendering the latter effective to supply an energy impulse to the fence wire.

15. Apparatus for energizing a fence comprising a conductive wire adapted to be placed in circuit with the body of an animal contacting the wire, including in combination, energy impulse supplying means coupled to the fence wire adapted to supply an energy impulse to the wire, means including a low voltage control means coupled to the fence wire and controlling said first mentioned means and controlled in response to contact between the wire and the body of an animal for rendering said first mentioned means effective to supply an energy impulse through the fence circuit, and means coupled to said low voltage control means for limiting the application of high voltages such as might be induced by lightning upon said low voltage means.

16. Apparatus for energizing a fence comprising a conductive wire adapted to be placed in

circuit with the body of an animal contacting the wire, including in combination, means including normally inoperative high voltage energy impulse supplying means coupled to the fence wire adapted when rendered operative to supply an energy impulse to the fence wire, means including an amplifier controlling said last mentioned means and having its input connected to the fence wire and operable upon contact between the wire and the body of an animal for rendering said impulse supplying means operative, and means including a normally nonconductive gas discharge tube connected across the input of the amplifier for indicating operation of the apparatus and for limiting the voltage input to said amplifier.

17. Apparatus for energizing a fence comprising a conductive wire adapted to be placed in circuit with the body of an animal contacting the wire, including in combination, a low voltage source of power and a pair of branch circuits leading therefrom, normally inoperative energy impulse supplying means coupled to the fence wire including a condenser connected to and normally charged from first of said branch circuits, a transformer having a primary winding connected to and through which the condenser is adapted to be discharged and which is inductively connected to the fence for supplying a high voltage energy impulse to the fence wire and an electron tube in series with said primary winding for effecting the discharge of said condenser through said winding and the tube, means connecting the second branch circuit to the wire for applying a control voltage to the wire, means coupled to the fence wire for producing a control voltage when an animal contacts the wire, and amplifier means coupled to said last mentioned means and controlling said tube and operable upon a change in current flow in the fence circuit for rendering said tube conductive to discharge said condenser through said primary winding and tube.

18. Apparatus for energizing a fence comprising a conductive wire adapted to be placed in circuit with the body of an animal contacting the wire, including in combination, a low voltage source of power and a pair of branch circuits leading therefrom, normally inoperative energy impulse supplying means including a condenser connected to and normally charged from a first of said branch circuits, a transformer having a primary winding connected to the condenser through which the condenser is adapted to be discharged and which is inductively connected to the fence wire for supplying a high voltage energy impulse to the fence wire and means for effecting the discharge of said condenser, means including a circuit including a resistor for applying a control voltage to the fence circuit from the second of said branch circuits, means including an amplifier connected to said resistor circuit operable upon a change in current flow through said resistor for operating said discharge effecting means, the input of said amplifier being coupled to the resistor circuit through a series connected resistor and a condenser, and a gas discharge tube shunting said resistor and condenser.

19. Apparatus for energizing a fence comprising a conductive wire adapted to be grounded electrically through the body of an animal contacting the wire, including in combination, voltage supplying means adapted to be coupled to the fence wire for normally applying a voltage to the fence wire, energy impulse supplying means adapted to be coupled to the wire adapted to sup-

ply an energy impulse to the fence wire, and change responsive means adapted to be coupled to the wire and controlled in response to changes in current flow resulting upon contact between the wire and the bodies of animals and controlling said last mentioned means for rendering the latter effective when a change in current flow occurs upon contact to supply successive impulses of energy to said wire in response to successive contacts between the fence wire and animals.

20. Apparatus for energizing a fence comprising a conductive wire adapted to be placed in circuit with the body of an animal contacting the wire, including in combination, a voltage source, a condenser, means connecting the condenser to the voltage source for charging said condenser from said source, means including an electron tube connected to the condenser and through which the condenser is adapted to discharge for producing a single impulse energy discharge through the fence circuit and the body of an animal when the animal contacts the wire, means adapted to be coupled to the fence wire for producing a change in an electrical characteristic when an animal contacts the fence wire, and means adapted to be coupled to said last mentioned means and controlling the conductivity of said tube in response to changes in said electrical characteristic occurring at a predetermined rate and rendering said tube conductive in response to said change to supply an energy impulse.

21. Apparatus for energizing a fence comprising a conductive wire adapted to be placed in circuit with the body of an animal contacting the wire, including in combination, a first voltage source, means including a resistor adapted to connect said voltage source to said wire, a second voltage source, a condenser connected to said second voltage source to be charged thereby, means adapted to be coupled to the fence wire and including an electron tube connected to said second source and across said condenser for effecting the discharge of said condenser to provide a shocking impulse across the fence circuit, and means coupled to said resistor and tube and controlled in response to the voltage drop across said resistor for controlling the conductivity of the tube.

22. Apparatus for energizing a fence comprising a conductive wire adapted to be placed in circuit with the body of an animal contacting the wire, including in combination, energy impulse supplying means adapted to be coupled to the fence wire including a normally nonconductive electron tube for supplying an energy impulse to the fence wire, means adapted to be coupled to the fence wire for producing a change in an electrical characteristic when an animal contacts the wire, and means including change responsive means having a predetermined change response coupling the tube to said last mentioned means and controlling the conductivity of said tube in response to a change in an electrical characteristic of the fence wire occurring at a predetermined rate for rendering said tube conductive in response to a change occurring upon contact between the wire and an animal, and means associated with said tube for preventing said tube from being rendered conductive in response to a change occurring upon disengagement of the animal from the wire.

23. Apparatus for energizing a fence comprising a conductive wire adapted to be placed in circuit with the body of an animal contacting

the wire, including in combination, energy impulse supplying means coupled to the fence wire including a normally nonconductive grid controlled electron tube for supplying an energy impulse to the fence wire, means including a resistor coupled to the fence wire and a condenser coupling the resistor to the grid of the tube for rendering the grid potential of said tube more positive in response to a change in an electrical characteristic of the fence circuit occurring at a predetermined rate for rendering said tube conductive in response to a change occurring upon contact between the wire and an animal, and means normally biasing the tube to cutoff for preventing said tube from being rendered conductive in response to a change occurring upon disengagement of the animal from the wire.

24. Apparatus for energizing a fence comprising a conductive wire adapted to be placed in circuit with the body of an animal contacting the wire, including in combination, energy impulse supplying means adapted to be coupled to the fence wire and adapted to supply a single shock of brief duration to the fence wire, means also adapted to be coupled to the fence circuit for producing an electrical change when an animal contacts the fence wire, and electrical change responsive means coupled to said last mentioned means controlled in response to said electrical change occurring upon contact between the wire and the body of an animal and controlling said first mentioned means for rendering the latter operative to supply a single shock of brief duration.

25. Apparatus for energizing a fence comprising a conductive wire adapted to be placed in circuit with the body of an animal contacting the wire, including in combination, energy impulse supplying means adapted to be coupled to the fence wire and adapted to supply a single energy impulse to the fence wire, means adapted to be coupled to the fence wire for producing an electrical change when an animal contacts the fence wire, and electrical characteristic change responsive means coupled to said last mentioned means effective in response to changes in an electrical characteristic, occurring at a predetermined rate, resulting upon contact between the wire and the body of an animal, and controlling said first mentioned means for rendering the latter operative in response to such a change to supply a single energy impulse.
